UNITED STATES PATENT OFFICE

GARLAND G. DORMAN, OF COLVILLE, WASHINGTON

COLLAPSIBLE CAMP STOVE

Application filed August 19, 1929. Serial No. 386,990.

This invention relates to a collapsible camp stove, the essential qualities of which are cheapness, lightness, strength and durability combined with ease and rapidity in setting up and taking down and which can be folded compactly in a small space and yet capable of heating and cooking with high efficiency.

Another object is to so construct a stove of this character which while highly efficient as a heater and cook stove is composed of a minimum number of parts which when assembled and set up will provide a collapsible air tight heater and cook stove.

Another object is to so construct and connect the sections as to render them resistant to warping incident to the use of thin gauge metal and which if warped may be easily straightened out.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a perspective view of a stove constructed in accordance with this invention set up ready for use;

Fig. 2 is a longitudinal section thereof taken on the line 2—2 of Fig. 1;

Fig. 3 is a horizontal section taken on the line 3—3 of Fig. 2;

Fig. 4 is a perspective view showing the stove collapsed with the members partly separated; and

Fig. 5 is a detail perspective view of one of the corners of the stove showing the connection between the side and end members.

In the embodiment illustrated the stove constituting this invention is composed of five sections. The front section 1, rear section 2, and side sections 3 and 4 which are designed to be connected at the ends in a manner presently to be described and are held in assembled position by means of a top 5 provided with a circumstantially extending flange 6 which slips down over the upper ends of the side and end members and holds them rigidly connected. The front and rear

sections are provided along the ends thereof with grooved guides 7 which are folded twice to reinforce and strengthen them at this point and provided with an opening groove to receive longitudinally extending flanges 8 carried by the ends of the side members 3 and 4 which are slidably mounted in the guides 7, thereby forming air tight joint connections at these points.

The side and end members of the stove are provided at their upper ends above the grooves and flanges 7 and 8 with upstanding flanges 9 over which is designed to be mounted the flanged top 5, the flange 6 of said top fitting over and outside the flanges 9 of the members and holding the parts rigidly connected.

The top 5 is provided at one corner, preferably at one of the rear corners, with a stove pipe receiving opening 10 which has a depending inwardly extending collar 11 around it to receive and support a stove pipe, not shown.

The front member 1 of the stove, as shown, is provided with a hinged door 12 held closed by any suitable fastening means, a swinging latch bar 13 being here shown adapted to enter a keeper carried by the front member, as shown, clearly in Fig. 1.

The flanges 6 of the top 5 are shown extended at the corners of the top and folded down and riveted to the adjacent flange (see Fig. 1).

This stove has no bottom and is designed to be set right on the ground and have a part of the earth dug out at the front thereof to afford ample draft for burning, the door 12 permitting access to the interior.

By extending the collar 11 inwardly instead of outwardly the top member 5 when disassembled may be compactly packed and when in use it will support a pipe.

The tapering of the front, rear and side walls of the stove members towards the top thereof provides a solid reliable support, this also provides for the drawing away of heat from the top of the stove for the purpose of cooking.

In the collapsing of this stove the parts are separated and placed one upon the other

with the top of the stove fitting in last so that the stove when collapsed will occupy a minimum amount of space and when desired for use these parts may be quickly assembled 5 by slidably engaging the front and rear members with the ends of the side members and then placing the top over the upper projecting edges or flanges of these members thereby securely locking them together in 10 air-tight rigid relation. It will thus be seen that the corner construction of the stove in connection with the relative position of the side members with the top constitutes the gist of the invention.

15 Without further description it is thought that the features and advantages of the invention will be readily apparent to those skilled in the art, and it will, of course, be understood that changes in the form, proportion 20 and minor details of construction may be resorted to, without departing from the spirit of the invention or its scope as claimed.

I claim:

25 1. A knock down, sheet metal stove comprising end and side members tapering from their lower toward their upper ends and adapted to be interlockingly engaged, one of said members having a double inturned fold 30 to form a vertical guide and the other having a longitudinally extending flange to fit in the guide, the upper ends of said side and end members having extensions above the flanges and guides thereof, and a top having 35 a depending flange adapted to fit over said extensions and securely hold said sides and ends in operative position.

2. A knock down, sheet metal stove comprising end and side members tapering from their lower toward their upper ends and adapted to be interlockingly engaged, one of said members having a double inturned fold 40 to form a vertical guide and the other having a longitudinally extending flange to fit in the guide, and a top to fit snugly over the upper ends of said members to hold them rigidly assembled, said top member having 45 a pipe receiving aperture therein provided with a depending collar extending into the interior of the stove.

50 GARLAND G. DORMAN.
